DESK FILE

Steve A. Unger, 343 S. Jefferson, Woodstock, Ill. 60098

Filed Feb. 16, 1972, Ser. No. 227,018

Term of patent 14 years

Int. Cl. D19—02

U.S. Cl. D74—2 A

FIG. 1

FIG. 2

FIG. 3

FIG. 4

FIG. 5

FIG. 1 is a perspective view of a desk file showing my new design having four drawers and a shelf as it appears with a side outer wall partially broken away for convenience of illustration;

FIG. 2 is a front elevational view of another embodiment of the desk file shown in FIG. 1 having only four file drawers;

FIG. 3 is a front elevational view of the desk file shown in FIG. 1;

FIG. 4 is a perspective view of the desk file shown in FIG. 2;

FIG. 5 is a side elevational view of the desk file shown in FIGS. 2 and 4 as it appears with part of the outer wall and inner drawer support wall broken away for convenience of illustration.

I claim:

The ornamental design for a desk file, as shown and described.
